**SYSTEM FOR DISCHARGING STACKED
GRANULAR MATERIAL**

Erwin Bührer, Schaffhausen, Switzerland

Application July 22, 1957, Serial No. 673,345

Claims priority, application Switzerland July 27, 1956

9 Claims. (Cl. 222—199)

The present invention relates to method and means for discharging granular material, in particular, but not exclusively for use in foundry molds.

It is known to strew granular material upon a surface by passing this granular material through a sieve. Such known process has, however, the disadvantage that the amount of granular material strewed onto the surface varies to a great extent and within wide limits, may differ with respect to quantity of the material at various areas. Moreover the deposit of the sieved out granular material along marginal surface portions cannot be obtained with sufficient accuracy. A further disadvantage is that only relatively small quantities of material per time unit may be deposited onto a surface by this known method.

It has also been proposed to fill pulverized glass from a container into molds by using as the bottom of the container a grid structure and by oscillating this grid structure by means of electromagnetic means.

Moreover, it is known to provide a silo with a grate-like bottom and to move rods of a movable grate member between the rods of a stationary grate member. This movement may either be a horizontal reciprocatory movement or a combined vertical and horizontal reciprocatory movement, so that the granular material loosened up by this movement may pass through the spaces between the rods of the stationary grate member in a regulatable manner. It is further known to strew granular material by subjecting a non-resilient and substantially rigid grid supporting said granular material, to a vibratory movement.

If granular material is to be dispensed in large quantities per time unit from a silo the above described methods and means may not be used due to the fact that either the spacing between the rods of the oscillating grate member would have to be so large, that in position of rest such grate member would be unable to safely support and maintain the granular material above said grate.

Alternatively, if a smaller spacing between these rods were chosen the amount of granular material to be discharged would be reduced in a non controllable and uneven manner due to the precompaction of this granular material above the grate. Such precompaction of the granular material above the discharge grate is, however, always undesirable.

It is, therefore, an object of the present invention to provide means enabling discharge of granular material from a storage or like space through even distribution and in a relatively loose state and manner.

A further object of the present invention is to provide a novel system of delivering a relatively large quantity of granular material per time unit in a controlled manner of distribution.

Still a further object of the present invention is the provision of means rendering the possibility of supporting granular material within the storage space in stationary condition and to discharge such granular material thereafter at will, so that the material assumes a con-

2

dition of movement, by gravity and at a predetermined state which does not require any after-treatment.

Another object of the present invention is to provide means for discharging granular material from a storage space and for preventing precompaction to a considerable extent of said material prior to or during such discharge movement.

A further object of the present invention is to provide means facilitating support of said granular material in one position, preferably in a position of rest, and imparting to said material a cutting action while said granular material is being released for discharge from said support to contribute certain characteristics and properties to said granular material, which are desirable in foundry mold production and for other purposes, such as in the plastic industry, powder metallurgy and ceramic technique employing granular materials.

Another object of the present invention is the provision of means permitting a plurality of grate rods or members in a position of rest to support granular material thereabove, while same assumes an arch- or bridge-shaped configuration; whereas in an operative position in which said grate rods or members perform non-uniform oscillatory motions relative to each other and in a vertical direction said bridge-shaped configuration will be subjected to constant changes, thereby depriving said granular material while bringing the latter into a loose state, of its support and consequently causing same to be discharged between said grate rods.

Still a further object of the present invention is the provision of means conducive to the structure of a grate assembly at the lower end of a storage receptacle or silo, as well as at a location adjacent to said lower end, which grate assembly permits safe storage and retainment of said granular material during a condition of rest and discharge of said material in predetermined quantity and texture for subsequent use.

It is still another object of the present invention to provide means forming a plurality of grate members arranged for oscillatory up and downward movements relative to each other, and to provide further means to effect said up and downward movements of said grate members at predetermined displacement of phase.

A further object of the present invention is the provision of oscillation generating means for controlling the movements of said grate members to be carried out in a relationship of displacement of phase.

Another object of the present invention is the provision of a discharge device adapted to deliver molding sand from a storage receptacle directly into a mold box and above pattern means arranged therein in a manner so as to bring about uniform and even loose state of said sand around said pattern means and throughout said mold.

Further objects and advantages will become apparent from the following detailed description, reference being made to the accompanying drawings, showing a preferred embodiment of the invention.

In the drawings:

Fig. 1 is a section taken along line I—I of Fig. 3, showing material discharge means embodying the present invention to facilitate strewing of granular material in a loose manner.

Fig. 2 is a section taken along lines II—II of Fig. 1.

Fig. 3 is a side elevation of Fig. 1, as seen in the direction of arrow A.

Fig. 4 is an elevational fragmentary view of a part shown in Fig. 5, as seen in the direction of arrow B.

Fig. 5 is an elevational fragmentary view of said part of Fig. 4, as seen in the direction of arrow C.

Fig. 6 is an elevational view, as seen in the direction

of arrow D in Fig. 7, a partial section being taken along line VI—VI of Fig. 7.

Fig. 7 is an elevational view, partly in section, as seen in the direction of arrow E in Fig. 6, the section being taken along lines VII—VII of Fig. 6.

Fig. 8 is an elevational view, as seen in the direction of arrow F of Fig. 9, parts being shown in section, taken along lines VIII—VIII of Fig. 9.

Fig. 9 is an elevational view, as seen in the direction of arrow G of Fig. 8, a section being taken along lines IX—IX of Fig. 8.

Fig. 10 is a modification of the material discharge means of Figs. 1 to 3, shown schematically and in vertical section.

Figs. 10a—10c are respective schematic representations of three different relative positions of the grate rods employable in the modification shown in Fig. 10.

Referring now more particularly to the attached drawings, there is disclosed in Figs. 1 to 3 a device or equipment which comprises a frame 2 supported by standards 1 from a support structure (not shown). Frame 2 forms a chamber 3 which is filled out by lead. On the frame 2 a silo 5 is supported by means of brackets 4, which silo contains granular material 6. In addition the frame 2 carries an electric motor 7, which is operatively connected with shafts 8 and 9 via couplings 10 and 11, respectively. Shaft 8 is rotated by motor 7 and drives via a pair of bevel gears 12, a shaft 13, whereas shaft 9 imparts rotation through a pair of bevel gears 14 to a shaft 15. An upper grate member 16 is suspended from four connecting rods 17, which are journaled in excenter bearings 18 of shafts 13 and 15, respectively. A lower grate member 19 is suspended from connecting rods 20, which are journaled on shafts 13 and 15, respectively, in excenter bearings 21 thereof. Rods 22 mounted on the frame 2 carry biased springs 23 and 24, which resiliently support the upper grate member 16 at their internal flanges 27 and which in turn abut against shoulders 25 and 26, respectively. Respective pairs of springs 29 and 30 abut against shoulders 26 and 28, respectively, and support the lower grate member 19 on flanges 31 thereof. The upper grate member 16 is provided with carrier bars or rods 32, which together with the corresponding grate member frame support grate rods 33. The lower grate member 19 comprises carrier bars or rods 34 supporting grate rods 35.

The carrier bars 32, on the one hand, are provided with recesses 36 which permit in upward direction a certain amount of play of the grate rods 35, which are rigidly connected to the carrier bars 34. The carrier bars or rods 34, on the other hand, are provided with recesses 37, which permit a corresponding amount of play, in downward direction, to the grate rods 33, which are rigidly connected with the carrier bars or rods 32.

In Fig. 1 the two grate members are shown to be in the position of rest, i.e. in a median position with respect to their amplitude of vibration or reciprocation. As will be seen from this Fig. 1 the upper edges of the grate rods 33 and 35 are positioned approximately on the same level in this median position. While it has been found that this arrangement of the grate rods is most suitable, it will be understood that a vertical displacement of the upper edges in the median position of the grate members 16 and 19 is also possible. The characteristics of the springs 23, 24, 29, and 30 are suitably chosen so that the springs may take up the acceleration forces of the grate members 16 and 19, respectively, when unloaded or in idle condition.

The device just described operates in accordance with Figs. 1 to 3 as follows in order to supply granular material:

When the electric motor 7 is put into operation, this motor rotates shaft 8 in the direction of arrow 39 via coupling 10 and pair of bevel gears 12, so that shaft 13 is rotated in the direction of arrow 38. Shaft 9 will si-

multaneously be rotated via coupling 11 in the direction of arrow 40, and this rotation is imparted to shaft 15 via pair of bevel gears 14 in the direction of arrow 41.

Due to the rotation of shafts 13 and 15 the eccentric bearings 18 and 21 effect an upward and downward movement of the grate members 16 and 19 via the connecting rods 17 and 20, respectively. Since the eccentric bearings 18 are displaced with respect to the eccentric bearings 21 by an angle of 180° the upward and downward movements or reciprocations of the upper grate member 16 are effectuated with a displacement of phase of 180° with respect to the upward and downward movements of reciprocations of the lower grate member 19.

The silo 5 containing granular material 6 serves to provide means for maintaining a minimum height of deposit or supply of material required for an even delivery of granular material throughout the whole area of the grate members.

When the motor 7 is not in operation the grate rods 33 and 35 and their particular position and spacing hold the granular material within the silo. The distance between the grate rods 33 and 35 correspond thereby substantially to the characteristics of the granular material. If the granular material consists of clay bound molding sand, the distance between two adjacent rods 33 and 35 is, for example, chosen to be between about 20 and 30 mm.

When the motor 7 is set in operation, the grate member 16 will, for instance, move upwardly, while the grate member 19 will carry out a downward movement. When the two grate members have reached the respective extreme positions of their reciprocations, their directions of movement are reversed.

Therefore, the grate member 16 will then perform a downward and the grate member 19 an upward movement. It will be understood that upon initiation of the reciprocating movement of the grate members the granular material will rest only on the grate rods 33 while after the reversal of the direction of movement the granular material will be supported only by the grate rods 35. This is due to the fact that the grate rods 33 and 35, respectively, during their downward movement will separate themselves from the granular material.

Due to the above described manner, a condition is reached which in operation corresponds substantially to twice the actual distance between two adjacent grate rods; furthermore, certain points of the granular material are alternatively subjected to pressure and to a reduced amount also to tension, i.e. a simulated cutting or loosening action is transmitted to the granular material.

Due to this measure a bridge formation between adjacent grate members is completely avoided and thereby an even and effective discharge of granular material during operation of the device is ensured.

Tests which were carried out with molding sand have shown that this arrangement of grate members is capable of depositing an amount of sand per time unit which is several times greater than the amount which may be deposited with conventional devices operating at equal reciprocation frequencies and amplitudes.

Moreover, the aforesaid arrangement of the present invention permits to reduce to a fraction undesirable compaction of the granular material above the grate rods as compared with conventional devices.

In an alternative arrangement of the apparatus arrangement shown in Figs. 1 to 3 it is possible to actuate the grate rods over individual eccentric bearings and to connect these rods so that in operation the behavior of the grate composed of these grate rods will correspond to a grate the grate rods of which are spaced from each other by three or four times the actual distance between adjacent grate rods.

The amplitude of reciprocation of the individual grate rods is preferably chosen so that only each third, fourth, etc. grate rod supports the material. As means for feeding granular material it is possible to arrange below a

silo a turning plate or turntable having a wiper member. In order to control the height of granular material supported above the grate, an electric feeler member may be arranged which determines the operation of the turning plate.

Figs. 4 and 5 show a modified form of a rectangular silo 42 while Figs. 6 and 7 show a modified form of an upper grate member 43 adapted for operation with silo 42 of Figs. 4 and 5. In Figs. 8 and 9 a modified form of a lower grate member 44 is shown.

Tests made in connection with the discharge of granular material in loose state have shown that, if the dimensions of the apparatus for effecting such discharge exceed in length and width certain measurements and if the cross-sections are rectangular, as is normally the case, it will be seen that in operation of the apparatus the granular material is in a less loose state in the central portions above the grate members than along the marginal portions thereof. In the corner areas of the grate members the granular material may be in such loose state that the entire granular material will fall through during operation. The modifications shown in Figs. 4 to 9 illustrate means which permit the discharge of even amounts of granular material over large rectangular cross-sections with a minimum and even precompaction of this granular material.

Figs. 4 and 5 show that the lower edge portions of silo 42 lie in a horizontal plane only at points 45 and along edges 46, whereas the remaining edge portions 47 and 48 are inclined towards marginal or end edges 49 defining the corners of the silo. In order to prevent a flow of granular material from silo 42 to the upper grate member 43 cooperating therewith, the upper silo 42 is provided at its corners with upwardly extending wall portions.

Due to the fact that the lower corner portions of silo 42 are cut off, the effect of increased friction is substantially compensated for, this friction normally being larger in the corner portions of the silo than in the central portion thereof. However, with the lower corner portions of the silo being cut away the friction in these corners is reduced to an amount which is substantially equal to the friction encountered in the central portions of the silo. The friction caused by the aforesaid elevated wall portions of the upper grate member is substantially compensated for by their reciprocation in operation of the apparatus.

It will be noted that spacing 53 between adjacent grate rods 54 of the upper grate member 43 and spacing 51 between grate rods 52 of the lower grate member 44 are larger than the spacings 56 and 55 between corresponding grate rods, spacings 53 and 51 being employed in the central portions of the grate members, whereas spacings 56 and 55 are applied to the marginal portions of said grate members. Due to this measure a further equalization of the depositing or discharging conditions over the full area of the grate is effected.

A further measure serving this end may be found in the configuration of the carrier rods 57 and 58, respectively. In order to further equalize the discharge of the granular material, the central carrier rods 57 of the grate member 43 are of greater height as indicated by edge 59, i.e. they extend deeper into the granular material than the carrier rods 58, the upper edges of which are indicated at 60.

Moreover, the height of these carrier rods is reduced adjacent the marginal portions of the respective grate member, as indicated at 61 and 62, respectively, i.e. these edge portions 61 and 62 are located on a substantially lower level than the edge portions 59 and 60, respectively.

It has been common practice to reciprocate the grates for dispensing or depositing granular material by means of electromagnets. However, investigations and tests have shown that the reciprocation amplitude of the grate is directly responsible for the amount of granular material to be discharged. If the characteristics of the granular material or the height of the granular material stored

above the grates change during operation, this change will, in grates driven by electromagnets, result in a variation of the reciprocation amplitude and therefore in a variation of the amount of granular material discharged per time unit. On the other hand, it is possible to maintain the amount of discharge substantially constant despite such changes, if the grates are reciprocated by means which ensure a constant reciprocation amplitude, such as eccentric rod means shown in Figs. 1 to 3.

If the discharge of granular material is to be effected intermittently and if the number of operating phases per time unit is very high, it is advisable to arrange between the drive motor and the shaft carrying the eccentric bearings, operable couplings or clutches which periodically engage said shaft while the drive motor operates continuously.

Referring now further to a modified embodiment schematically illustrated in Fig. 10 discharge means employing the grate members for handling granular material are shown. 70 indicates the lower end of a storage bin or silo for granular material, mounted in a manner similar to that of the silo of Fig. 1. Three grate members 72, 73, and 74 are arranged in superposed relation below silo 70 and supported on springs 75, 76, 77, 78, and 79, 20 respectively by means of bolts 71. It will be understood that bolts 71 corresponds to bolts 21, shown in Fig. 1.

The grate member 72 comprises a plurality of horizontally extending parallel grate rods 81 arranged on intermediate carrier means and in spaced relation to each other. Similarly grate member 73 comprises grate rods 82, while grate member 74 is provided with grate rods 83. It will be noted from Fig. 10 that the arrangement or sequence of the individual grate rods is such that they form a substantially continuous row in which a grate rod 82 follows a grate rod 83 and a grate rod 81 follows a grate rod 82, so that these grate rods are positioned in predetermined sequence over the whole length of said row.

If silo 70 is filled with granular material 84 this granular material will be supported in the position of rest by the grate rods 81, 82, 83 of the grate members 72 to 74. This due to the tendency of the granular material of assuming arch-shaped or bridge-shaped formations over the aforesaid support forming grate rods which within a certain maximum distance between two grate rods will prevent the granular material from sinking and flowing downwardly out of the silo 70.

Means not shown, but comparable to rods 17 and 20, eccentric bearings 18 and 21, shafts 13 and 15 and drive motor 7 seen in Figs. 1 to 3, are provided to impart to each of the grate members 72 to 74 an individual reciprocating up and downward movement. To this end, each one of the three grate members will be operatively connected to four eccentric bearings over four connecting rods, the eccentric bearings connected to one grate member being angularly displaced with respect to a second grate member and the latter being angularly displaced with respect to the eccentric bearings of the third grate member, so that upon operation of a drive motor the individual grate members and consequently their grate rods will reciprocate with a displacement of phase.

Whereas this displacement of phase is suitably chosen to be 180° in the case of two grate members working together as in the embodiment of Figs. 1 to 3, this displacement of phase is 120° according to the modification shown in Fig. 10.

Figs. 10a to 10c depict the relative positions of the grate rods in three different phases of movement of the grate members. In Fig. 10a the grate rods 83 are shown to assume an upper extreme position, while simultaneously grate rods 82 and 81 are in respective lower extreme positions. Fig. 10b shows grate rods 82 in an upper ex-

treme position, whereas grate rods 81 and 83 take up a lower extreme position. Fig. 10c indicates grate rods 81 in an upper extreme position and grate rods 82 and 83 in a lower extreme position.

Due to the operation of the grate member assembly, as described in connection with Figs. 10a to 10c the effect of the grate rods upon the granular material is comparable to an arrangement in which the distance between adjacent grate rods is three times greater than the distance shown in Fig. 10. Consequently, the granular material supported by the grate rods in a position of rest of the aforesaid assembly or device is not only brought into a looser state than by means of the device of Figs. 1 to 3 having only two individually reciprocating grate members, but also a greater quantity of granular material may thus be discharged from silo 70. In addition this device according to Fig. 10 permits to discharge in a more loose state the granules of said material having possibly a strong tendency to bind or stick together, due to the differentiated reciprocating motions of the three grate members, i.e. of the grate rods thereof.

From the above it will be understood that devices may be constructed in accordance with the present invention having four or more individually reciprocating grate members, the grate rods of which forming a composite grate. Furthermore, the number of grate members to be employed may be chosen in accordance with the properties of the granular material; a granular material of low binding tendency necessitating a smaller and a material of high binding tendency necessitating a greater number of individually reciprocating grate members.

The theory which is fundamental for the system and device of discharging granular material according to the present invention and in a manner described hereintofore will now be explained in greater detail. It may be assumed that the granular material is supported above the grate rods of very narrow width due to its tendency of producing arch-shaped or bridge-like configurations at the lowermost end. At a given distance a predetermined type of granular material will due to this tendency become self-supporting over the grate rods and, therefore, discharge of the material through the grate members in their predetermined position of rest is prevented. An increase in distance between adjacent grate rods will reduce the firmness of support of the granular material above these grate rods, i.e. the possibility of discharge increases with increasing distance between said grate rods.

At a critical distance between adjacent grate rods a small increase therein may bring about a destruction or collapse of the arch or bridge formation in the mass of granular material and therewith an unintentional discharge of the granular material in a position of rest of the grate rods.

The critical distance between adjacent grate rods in a position of rest is, however, largely a function of the condition and composition of the granules of material. In loose state a predetermined type of granular material will have a lesser tendency of assuming an arch formation than in a precompacted state. This factor is to a certain extent adverse to the discharge of granular material, since the reciprocation of the grate rods will bring about a precompaction of the granular material when in contact therewith. As a consequence thereof, the amount of granular material will, therefore, be considerably reduced due to this precompaction.

In order to discharge granular material in a controlled manner, it becomes, therefore, necessary to change the condition of support of the stacked granular material which gives rise to the aforesaid arch or bridge formation between the position of rest, i.e. when the material is stored, and the position of movement, i.e. when the material is to be discharged.

To this end, the present invention makes use of a grate

assembly in which adjacent grate rods carry out different reciprocating motions, whereby the distance between the points or lines of support of the granular material is increased in said position of motion with respect to said position of rest. In accordance with the number of grate units or members employed the increase in distance may be two, three or four times the initial distance due to the fact that with an assembly having two grate members only each second, with an assembly having three grate members only each third, etc. grate rod carries out equal movements and, therefore, will support the granular material. It is, therefore, understood, that while the granular material may safely be supported above the grate members in said position of rest, discharge of granular material in a very loose state being insured during operation or movement of the grate members, even if the granules of the material may have a strong tendency of binding together, undesirable discharge of the material during said position of rest being absolutely avoided.

Various changes and modifications may be made without departing from the spirit and scope of the present invention and it is intended that such obvious changes and modifications be embraced by the annexed claims.

Having thus described the invention, what is claimed as new and desired to be secured by Letters Patent, is:

1. A system for discharging granular material from a storage receptacle, comprising at least two grate members arranged in superposed relation below said storage receptacle, said grate members being arranged to effectuate from a position of rest upward and downward movements independently of each other and having each a plurality of horizontally extending grate rods, said grate rods of said grate members forming together in said position of rest a substantially horizontal row in predetermined relative vertical positions of said grate members, said grate rods connected to the one of said grate members alternating with said grate rods connected to the other of said grate members in said row, adjacent grate rods in said row being spaced in a horizontal plane from each other a distance sufficient to prevent said granular material in said storage receptacle from being discharged therefrom in said position of rest, thereby substantially supporting said granular material in said storage receptacle, reciprocation generating means operatively connected with each of said grate members, said reciprocation generating means being adapted to effect said upward and downward movements of said grate members into and out of said position of rest and being arranged with respect to each other to effect a displacement of phase in said movements, drive means connected to said reciprocation generating means for actuating same, said upward and downward movements of said grate members bringing about a loosening action of adjacent ones of said grate rods upon said granular material, whereby said granular material will be evenly discharged from said storage space through said grate members and between said grate rods thereof over large cross-sectional areas.

2. A system for discharging stacked granular material normally stored in a silo and like space; comprising a plurality of successively arranged and superpositioned grate means disposed for phase-controlled reciprocating motion in up- and downward directions relative to each other, a plurality of grate rod means mounted on each of said grate means and spaced from each other a predetermined distance, means for controlling and varying the phase of reciprocating motion of said grate means, and means for maintaining in a position of rest said grate means with said rod means to support said stacked material for imparting said reciprocating motion to said grate means, respectively, in predetermined phase displacement relation during said motion of said rod means, to discharge stacked material in a substantially loose state from said silo space into a receptacle.

3. A system according to claim 2, the reciprocating motion of one of said grate means having a displacement

of phase of 180° with respect to the oscillatory motion of another of said grate means.

4. A system according to claim 2, the distance of said grate rod means from each other of one of said grate means differing from the distance of the grate rod means of the other of said grate means. 5

5. A system for discharging stacked granular material normally stored in a silo and like space; comprising a plurality of successively arranged and superpositioned grate means disposed for phase-controlled reciprocating motion in up- and downward directions relative to each other, a plurality of grate rod means mounted on each of said grate means and spaced from each other a predetermined distance, means for controlling and varying the phase of reciprocating motion of said grate means, and means for maintaining in a position of rest said grate means with said rod means to support stacked material and for imparting said reciprocating motion to said grate means, respectively, in predetermined phase displacement relation during said motion of said rod means, to discharge stacked material in a substantially loose state from said silo space into a receptacle, the distance of said grate means rod means from each other of one of said grate means differing from the distance of the grate rod means of the other of said grate means, the distance between said grate rod means from each other being greater adjacent the center of one of said grate means than the distance between said grate rod means remote from said center of said one grate means, and wherein the distance between said grate rod means adjacent the center of another of said grate rod means is greater than the distance between the grate rod means of another of said grate means, the distance between said grate rod means adjacent the center of said one grate means differing from the distance of said grate rod means adjacent the center of said other grate means. 20

6. A system for discharging stacked granular material normally stored in a silo and like space; comprising a plurality of successively arranged and superpositioned grate means disposed for phase-controlled reciprocating motion in up- and downward directions relative to each other, a plurality of grate rod means mounted on each of said grate means and spaced from each other a predetermined distance, means for controlling and varying the phase of reciprocating motion of said grate means, and means for maintaining in a position of rest said grate means with said rod means to support stacked material and for imparting said reciprocating motion to said grate means, respectively, in predetermined phase displacement relation during said motion of said rod means, to discharge stacked material in a substantially loose state from said silo space into a receptacle, the distance between the grate rod means of one of said grate means differing from the distance between the grate rod means of another of said grate means and the distance between the grate rod means of a further grate means being larger than the distance between the respective grate rod means of said one grate means and of said other grate means. 25

7. A system for discharging stacked granular material normally stored in a silo and like space; comprising a plurality of successively arranged and superpositioned grate means disposed for phase-controlled reciprocating motion in up- and downward directions relative to each other, a plurality of grate rod means mounted on each of said grate means and spaced from each other a predetermined distance, means for controlling and varying the phase of reciprocating motion of said grate means, and means for maintaining in a position of rest said 70

grate means with said rod means to support stacked material and for imparting said reciprocating motion to said grate means, respectively, in predetermined phase displacement relation during said motion of said rod means, to discharge stacked material in a substantially loose state from said silo space into a receptacle, wherein said grate rod means of the uppermost of said grate means being of greater height adjacent the center of said uppermost grate means than the height of the grate rod means remote from said center of said uppermost grate means. 10

8. A system for discharging stacked granular material normally stored in a silo and like space; comprising a plurality of successively arranged and superpositioned grate means disposed for phase-controlled reciprocating motion in up- and downward directions relative to each other, a plurality of grate rod means mounted on each of said grate means and spaced from each other a predetermined distance, means for controlling and varying the phase of reciprocating motion of said grate means, and means for maintaining in a position of rest said grate means with said rod means to support stacked material and for imparting said reciprocating motion to said grate means, respectively, in predetermined phase displacement relation during said motion of said rod means, to discharge stacked material in a substantially loose state from said silo space into a receptacle, the space of said silo and the uppermost grate means being defined by respective walls, the walls of said silo and the walls of said uppermost grate means providing substantially polygonal formations, respectively, the walls of said silo at the lowermost end of the latter being shaped so that the height of said walls thereof is shorter at the corners of said silo than at the remaining wall portions thereof, the walls of said uppermost grate means being greater in height at edges of said uppermost grate means located adjacent said corners of said lowermost end of said silo. 20

9. A system for discharging granular material from a storage space; comprising a plurality of grate means forming the bottom of said storage space and extending in spaced horizontal relation to each other, said grate means being arranged for movement in upward and downward directions, at least one of said grate means being arranged for upward and downward movement independently of an adjacent one of said grate means, a plurality of reciprocation generating means, one of said reciprocation generating means being connected to at least one of said grate means, another of said reciprocation generating means being connected to at least another of said grate means arranged adjacent said one grate means, and drive means connected to said reciprocation generating means to operate the latter whereby in a position of rest of said grate means said granular material will be supported above the latter, whereas upon operation of said reciprocation generating means said granular material will flow downwardly within the confines of said grate means, said reciprocation generating means being adapted to impart to said grate means upward and downward movements in a phase displacement relation to each other, to thereby bring said material into a loose state and to increase and provide a substantially uniform downward flow of said granular material from said storage space. 30
